UNITED STATES PATENT OFFICE.

NICHOLAS FOX, OF LAKE ANDES, SOUTH DAKOTA.

WASHING MACHINE.

Application filed May 20, 1922. Serial No. 562,288.

My invention relates to improvements in washing machines, and it consists in the combinations, constructions, and arrangements herein described and claimed.

5 An object of my invention is to provide a washing machine of the character described in which the cover that supports the oscillating dolly may be opened while the device is in operation to observe the condition 10 of the contents of the washer without first disconnecting manually any part of the mechanism.

A further object of my invention is to provide a washing machine of the character 15 described having wringer rolls and means for releasing the tension of the wringer rolls at both ends as in the event of an accident or the like, the means for releasing the rolls being entirely disposed beneath the 20 rollers. This novel structure does away with the ordinary type of safety device that is mounted at the top of the rollers, and in most cases, prevents the observation of the rollers while they are in operation.

25 A further object of my invention is to provide a washing machine of the character described in which the wringer may be swung in a horizontal plane and locked in a predetermined position while the device 30 is in operation.

A further object of my invention is to provide a device of the character described that is extremely simple in construction, and thoroughly practical for the purpose intended.

35 Other objects and advantages will appear in the following specification, and the novel features of the invention will be particularly pointed out in the appended claim.

40 My invention is illustrated in the accompanying drawings, forming part of this application, in which

Figure 1 is a top plan view of an embodiment of my invention,

45 Figure 2 is a side elevation, partly in section, of the mechanism illustrated in Figure 1 with the gear case cover removed,

Figure 3 is a sectional view along the line 3—3 of Figure 2,

50 Figure 4 is a sectional view along the line 4—4 of Figure 2,

Figure 5 is a sectional view along the line 5—5 of Figure 2,

55 Figure 6 is a sectional view along the line 6—6 of Figure 2, and

Figure 7 is a sectional view along the line 7—7 of Figure 1.

In carrying out my invention, I make use of a washing tub 1 of metal or other suitable material. The tub 1 is provided with a 60 cover 2 hingedly mounted thereto by hinges 3.

A dolly 4 is rotatably mounted on the cover 2, the central shaft 5 thereof extending up through the top 6 of the cover. A 65 gear wheel 7 is carried by the upwardly extending portion of the shaft 5, as shown in Figure 7.

A second gear 8 is rotatably mounted on the cover 2 and has its teeth in mesh with 70 the gear 7. Means for oscillating the gear 8 so that the dolly 4 may be driven with an oscillatory movement is provided as follows.

A gear housing 9 is supported upon the 75 washer 1 adjacent the cover 2. A vertical shaft 10 is rotatably mounted within the housing 7 and arranged to extend upwardly therefrom. A worm wheel 11 is carried by the shaft 10, and an eccentric plate 12 is 80 mounted in close proximity with the gear 11. A worm gear 13 is also mounted within the housing 9 and has its integral shaft 14 extending out of the housing. The worm gear 13 is arranged so that its teeth are at 85 all times in mesh with the gear 11. The worm gear 13 is driven by means of an electric motor 15 and a belt 16 which connects the motor 15 with a pulley wheel 17 carried by the shaft 14. 90

An outwardly extending supporting arm 19, forming an integral part of the housing 7, is provided and extends to a point in alignment with the gears 8 and 7 on the cover 2 when the cover is in place. A rock 95 shaft 20 is supported upon the extension 19 and a broken gear 21 is carried by the rock shaft 20. The gear 21 is operatively connected to the eccentric plate 12 by means of a pitman 22 so that rotation of the gear 11 100 is brought about by the operation of the motor 15, and will cause the eccentric plate 12 to move the pitman with a reciprocative movement and thus oscillate the gear 21.

The shaft 10, as described, extends upwardly from within the housing 9 and serves as a means to rotatably support a gear casing 23, a nut 24 being provided to limit the vertical movement of the casing 23 on the shaft 10. A pair of bevel gears 24 and 25 105

are keyed to the shaft 10 within the casing 23, and a third bevel gear 26 is rotatably mounted intermediate the gears 24 and 25 so that vertical movement of the gears 24 and 25 on the shaft 10 will cause them to alternately engage the gear 26.

Means for reciprocating the gears 24 and 25 on the shaft 10 is provided in a lever 27 operatively connected to a cam 28 disposed 10 between the adjacent surfaces of the gears 24 and 25. This is clearly shown in Figure 5.

The gear 26 is operatively connected to a pair of wringer rollers 29 and 30 rotatably supported upon an extension 31 of the casing 23 (see Figure 2).

Means for locking the casing 23 at any one of a predetermined number of positions in a horizontal plane, is provided in a plurality 20 of notches 32 in the top surface 33 of the housing 9, and a spring-pressed plunger 34 carried by the casing 23. The plunger 34 may be elevated out of engagement with the notches 32 by pressure upon a hand lever 25 35 operatively connected to the plunger 34, as shown in Figure 2.

Means for obviating the possibility of an accident by an operator catching his or her hands or clothing between the wringer rolls 29 and 30 is provided in a pair of loop members 36 arranged to engage the opposite ends of the roller 30, as shown in dotted lines in Figure 2. The lower ends of the members 36 are engaged by opposite ends 35 of a strong compression spring 38. A cam 39 (see Figure 6) is supported beneath the extension 31 and is adapted to be moved into engagement with the spring 38, whereby the spring is moved downwardly to force 40 the roller 30 in close engagement with the roller 29. Movement of the hand lever 40 connected to the cam 39 by a common shaft 41, will cause the cam 39 to move and disengage the spring 38, thus releasing the tension upon the roller 30.

From the foregoing description of the various parts of the device, the operation thereof may be readily understood. In using my washer, I first place water having soap 50 and other cleansing ingredients in the tub. I then insert the articles to be washed. The cover 2 is then closed and the motor 15 connected to a source of power.

The motor 15 will cause the worm gear 13 55 to rotate and drive the worm wheel 11. As

the worm wheel 11 operates, the pitman 22 will reciprocate and cause the gear 21 to oscillate. Since the gear 21 is in mesh with the gear 8, and the gear 8 is in mesh with the gear 7, the dolly 4 will move with an oscillatory movement, i. e., a given number of revolutions one direction, and a subsequent and like number of revolutions in the opposite direction.

If it is desired to swing the rollers 29 60 and 30 to a certain point in the horizontal plane, it is merely necessary to press the hand lever 35 and manually swing the wringer to any desired position. It is not necessary to stop the operation of the machine in swinging the rollers.

To operate the rollers 29 and 30, as in wringing clothes, it is merely necessary to move the lever 27 to the right or to the left. Movement in one direction will cause the 70 rollers to revolve toward the top, and movement in the opposite direction will cause the rollers to rotate away from the top. When the lever 27 is in a vertical position, the rollers 29 and 30 do not move, since 80 the gear 26 is then out of mesh with the gears 24 and 25.

To release the tension of the roller 30, as in the case of an accident, it is merely necessary to manually move the lever 40. This 85 will instantly release pressure upon the spring 38, and the members 36 will relax in their engagement with the roller 30.

I claim:

A washing machine comprising a tub, a 90 cover hingedly mounted on said tub, a work-engaging mechanism operatively mounted on said cover and including a gear lying in a plane parallel with the cover and a second gear in mesh with said first named 95 gear and projecting beyond the edge of the cover, a mutilated gear mounted upon said tub and lying in the same plane as said first and said second named gears when said cover is in closed position, said mutilated 100 gear being adapted to mesh with said second named gear when said cover is in closed position, and power-actuated means for oscillating the mutilated gear, said cover being hinged along an edge disposed parallel with a line extending through the centers of said first and second named gears and said mutilated gear.

NICHOLAS FOX.
